UNITED STATES PATENT OFFICE

DRAKE BROOKSHIRE, OF GALENA, KANSAS

SAFETY TUBING LOCK

Application filed September 6, 1929. Serial No. 390,837.

This invention relates to a safety tubing lock particularly adapted for use in connection with deep oil wells or similar excavations for automatically attaching the tubing to the well casing to prevent loss of the tubing in case of breakage of the tubing from its support or when it is desired to stop the descent of the tubing into the well.

An object of this invention is to provide a safety tubing lock which will be positive in its action and which will quickly and securely hold the tubing in case of accident or which may be forced to operate to prevent further descent of the tubing when it is desired to stop the lowering of the tubing into the well.

Another object is to provide a device of the character referred to having an expandible member mounted on the tubing and capable of relative movement with respect thereto, a second relatively movable member being slidably mounted on the tubing and being adapted to expand the expandible member under certain conditions.

A further object is to provide a device of the character referred to wherein a float or other similar means is connected with the expandible member and movable therewith to positively cause differential movement between the tubing and the expandible member whereby the slidably expanding means on the tubing will be enabled to expand the expandible member.

A further object is to provide a device of the character referred to wherein the tubing is provided with means to strike a blow upon the upper surface of the slidably expanding means to force the latter into positive engagement with the expandible member.

Other objects and advantages of the invention will become apparent during the course of the following description.

In the drawings I have shown one embodiment of my invention. In this showing,

Figure 1 is a front elevation of the device arranged in a section of well casing,

Figure 2 is an enlarged vertical sectional view,

Figure 3 is a transverse sectional view

taken substantially on line 3—3 of Figure 2, and

Figure 4 is a perspective view of the expanding means.

Referring to the drawings the numeral 10 indicates a section of well casing or other tubular member into which it is desired to lower a string of tubing or the like, as will be understood. The numeral 11 indicates an upper section of well tubing joined to a short length of well tubing 12 by means of an internally threaded coupling 13. The ends of the sections of well tubing are threaded substantially as shown at 14 to be received in the coupling 13 and the latter is provided with a substantially oval-shaped upper surface, as indicated at 15. Beneath the section 12 of the well tubing is a lower section of tubing 16. As shown, the adjacent extremities of these sections of tubings are threaded as shown at 17 and an internally threaded coupling 18 is adapted to secure the sections of tubing together.

A substantially annular inverted cup-shaped member 19 is slidably mounted on the section of tubing 11 and its inner surface snugly engages the outer surface of the coupling 13 when the device is in the position shown in Figure 2. The lower portion of the member 19 has secured thereto the upper ends of a plurality of swingable arms 20 and the lower extremities of these arms are suitably secured to an expandible member 21. The member 21 is preferably formed of a pair of complementary sections 22 and 23 spaced to provide openings 24 between the complementary members in their normal inoperative position. Each complementary member is provided with a plurality of gripping teeth 25 arranged circumferentially, the purpose of which will become apparent. The diameter of the expandible member 21 is slightly less than the inside diameter of the well casing.

Adjacent its upper extremity the member 19 is internally threaded as at 26 and receives the externally threaded extremity 27 of a float 28 or other similar member. As shown, the float 28 is preferably formed with a hollow cylindrical body 29 provided with closure members 30 adjacent each extremity of

the body. Each closure member has a relatively long neck 31 extending longitudinally of the tubing. It will be apparent that the member 19, the expansible member 21 and 5 the float 28 are movable together and independently of the tubing.

Slidably mounted on the section of tubing 12 is a tapered expanding member or wedge 32 adapted to expand the expansible member 21 under certain conditions.

The operation of the device is as follows:

Well tubing equipped with the safety lock described is lowered into the well casing in the usual manner. During normal descent 15 of the tubing the parts of the locking means will remain in their inoperative position shown in Figure 2. However, if the tubing should break above the locking device the tubing will immediately begin to descend at 20 a greater rate of speed than it attains by being mechanically lowered. The inertia of the tubing will therefore tend to permit the tubing to drop more rapidly than the locking device. This differential movement between 25 the tubing and the locking device will, if the drop is of sufficient length, eventually cause the wedge 32 to expand the complementary members and cause the teeth of the latter to grip the interior of the well casing to prevent 30 further descent of the tubing. In order to insure that the differential movement between the locking means and the tubing is sufficient to quickly cause the locking means to function, I have provided the float 28, or other 35 equivalent means.

The float 28 is connected with the expansible member 21 and when the tubing begins to descend more rapidly than normal, the float serves to immediately check the increased downward movement of the expansible member. This downward movement of 40 the expansible member is not stopped entirely by the float, but the latter quickly causes a substantial differential movement 45 between the expansible member and the tubing, thus enabling the expanding means or wedge 32 to quickly engage the expansible member and force the teeth of the latter into engagement with the well casing.

50 In order to further insure quick and positive locking action of the expansible member, I have slidably mounted the wedge 32 on the tubing and the lower surface of the coupling 13 will strike a hard blow on the upper surface 55 face of the wedge thus forcing the latter into engagement with the expansible member.

If it is desired to stop the tubing during its normal descent and at the same time relieve the strain on the lowering mechanism, 60 the tubing may be permitted to suddenly drop at increased speed for a short distance and the locking device will operate, as will be apparent.

In order to unlock the device it is only 65 necessary to pull the tubing upwardly and

the coupling 18 will force the wedge 32 out of engagement with the expansible member.

It is to be understood that the form of my invention herewith shown and described is to be taken as a preferred example of the same and that various changes in the shape, size, and arrangement of parts may be resorted to without departing from the spirit of the invention or the scope of the subjoined claims.

I claim:

1. A tubing lock comprising an expansible member mounted for independent movement on the tubing, means slidable on the tubing for expanding said member, means on the tubing for supporting the expansible member in inoperative position, said last named means being operable upon differential movement of the tubing and the expansible member to engage said expanding means to force the latter to expand said expansible member.

2. A tubing lock comprising an expansible member mounted for independent movement on the tubing, means slidable on the tubing for expanding said member, means on the tubing for supporting the expansible member in inoperative position, and means for causing differential movement of said tubing and said expansible member, said supporting means being operable upon differential movement of the tubing and the expansible member to strike said expanding means a sharp blow to force the latter to expand said expansible member.

3. A tubing lock comprising an expansible member mounted for independent movement on the tubing, means for expanding said member also mounted for independent movement on the tubing, means on the tubing for supporting the expansible member in inoperative position, and means connected to said expansible member to cause differential movement between the latter and said tubing, said supporting means being operable upon differential movement of the tubing and the expansible member to engage said expanding means to force the latter to expand said expansible member.

4. A tubing lock comprising an expansible member mounted for independent movement on the tubing, means slidable on the tubing for expanding said member, a float slidable on the tubing and being movable with and connected to said expansible member, means on the tubing for supporting the expansible member in inoperative position, said last named means being operable upon differential movement of the tubing and the expansible member to strike said expanding means a sharp blow to force the latter to expand said expansible member.

5. A tubing lock comprising a substantially hollow expansible member mounted for independent movement on the tubing, a

tapered member slidably mounted on said tubing above said expansible member and adapted to expand the latter, a float slidable on the tubing above said expansible member, 5 connections between said float and said expansible member whereby the latter and the float will move as a unit, said float being adapted to cause differential movement of the tubing and the expansible member, means on 10 the tubing for supporting the expansible member in inoperative position, said last named means being operable upon differential movement of the tubing and the expansible member to engage said tapered member to force the latter to expand said expansible member.

In testimony whereof I affix my signature.
DRAKE BROOKSHIRE.
